FIG. 1

FIG. 4

FIG. 5

FIG. 3

FIG. 2

FIG. 7

FIG. 6

FIG. 1 is a perspective view of a bottle embodying my new design;

FIG. 2 is a side elevational view, the opposite side being substantially a mirror image of the side shown;

FIG. 3 is an elevational view looking from the left of FIG. 2;

FIG. 4 is a top plan view;

FIG. 5 is a bottom plan view;

FIG. 6 is a perspective view of another embodiment of my new design differing from the bottle of FIGS. 1 through 5 in that only one annular ring is provided below the neck portion; and

FIG. 7 is a perspective view of yet another embodiment of my new design, differing from the bottles of FIGS. 1 through 6 in that two annular rings are provided below the neck portion.

I claim:

The ornamental design for a bottle, as shown and described.
